UNITED STATES PATENT OFFICE

EVERETT C. CIRCLE, OF COALTON, OKLAHOMA.

STEAM WATER-HEATER.

1,176,701.

Specification of Letters Patent. Patented Mar. 21, 1916.

Application filed December 17, 1913. Serial No. 807,261.

To all whom it may concern:

Be it known that I, EVERETT C. CIRCLE, a citizen of the United States, residing at Coalton, in the county of Okmulgee, State 5 of Oklahoma, have invented certain new and useful Improvements in Steam Water-Heaters; and I do hereby declare the following to be a full, clear, and exact description of the invention, such as will enable others 10 skilled in the art to which it appertains to make and use the same.

This invention relates to improvements in water heaters and particularly to steam water heaters.

15 The principal object of the invention is to provide a simply and novelly constructed device for heating a continuous stream of water by injecting steam thereinto.

Another object is to provide a device of 20 this character in which the steam and water will be thoroughly and intimately mixed to produce hot water.

Other objects and advantages will be apparent from the following description when 25 taken in connection with the accompanying drawing.

In the drawing: Figure 1 is an elevation of my steam water heater. Fig. 2 is a vertical longitudinal sectional view therethrough, 30 partly broken away. Fig. 3 is a horizontal sectional view on the line 3—3 of Fig. 2 looking upwardly. Fig. 4 is a vertical longitudinal sectional view taken on the line 4—4 Fig. 2 and looking to the right. Fig. 5 is a 35 vertical section of the lower portion of the casing showing a modification thereof. Fig. 6 is a section on line 6—6 of Fig. 5 taken in the direction of the arrow, the cylindrical portion of the casing being omitted.

40 Referring particularly to the accompanying drawing, 10 represents an elongated casing having a globular lower end 11. The upper end of the casing is interiorly threaded and receives therethrough a steam nozzle 12.

45 In one side of the upper portion of the casing is a nipple 13 to which is connected a cold water conduit 14, and in one side of the globular portion below the nipple 13 is another nipple 15 to which is connected a 50 conduit 16 for conveying the heated water to the point of use. It will be noted that the

lower or inner end of the nozzle 12 is disposed below the lower side of the nipple 13, this end being contracted so as to form a small outlet opening 17. 55

In the use of the device, the nozzle being connected to a source of steam supply, water is permitted to flow into the casing from the pipe 14 and out through the pipe 16. When the proper flow of water is obtained, the 60 steam is turned on and caused to discharge into the water and cause the same to be whirled in the globular end of the casing. The steam thus thoroughly mixes with the 65 water and effectively heats the same before it passes through the pipe 16.

In the pipe 14 is a controlling valve 18 for regulating the flow of the cold water, while in the pipe 16 and the pipe 19 which is connected to the nozzle are respectively arranged the valves 20 and 21. These valves 70 control the outflow of heated water and the inflow of steam. It will thus be seen that by regulating the flow of the cold water, as well as the steam any degree of temperature 75 can be obtained from the natural low temperature of the water to the high temperature of the steam.

This device is particularly adapted for shower baths, and by attaching a spray nozzle 80 22 to the outer end of the pipe 16 a fine spray of water of the proper temperature can be obtained. When the device is used particularly and solely for shower bath purposes the nipple 15 is omitted and this side 85 of the end of the casing closed. The lower end of the casing is then provided with a plurality of openings 23 for forming the spray and a baffle wall 24 arranged below the nozzle 12 to prevent the direct discharge 90 of steam from the spray and to cause it to thoroughly mix with the water.

From the foregoing it will be seen that I have provided a simple and efficient device 95 of this character, and one which can be quickly and easily connected with the water system adjacent a steam plant.

What is claimed, is:—

A steam water heater comprising a mixing 100 chamber including a hollow spherical portion, a pipe of lesser diameter leading therefrom, a steam pipe engaged in the otherwise

free end of said pipe and having its end therein reduced and terminating intermediate of the pipe to form a nozzle, a cold water pipe communicating laterally with the first pipe in such position that its projected axis passes centrally through the intermediate portion of the nozzle and a hot water pipe extending from the spherical portion

at a point out of alinement with the first mentioned pipe.

In testimony whereof, I affix my signature, in the presence of two witnesses.

EVERETT C. CIRCLE.
